TIRE

Milton A. Klotz, Akron, Ohio, assignor to The Goodyear
Tire & Rubber Company, Akron, Ohio, a corporation
of Ohio

Application December 10, 1957, Serial No. 48,852

Term of patent 14 years

(Cl. D90—20)

Fig. 1 is a perspective view of a tire showing my new design, it being understood that the full line portion of the design is repeated throughout the circumference of the tire, the opposite side being substantially the same as that shown;

Fig. 2 is an enlarged fragmentary top plan view thereof;

Fig. 3 is an enlarged fragmentary side elevational view thereof, the tread design being omitted for convenience of illustration; and

Fig. 4 is an enlarged cross-sectional view through the tire taken on line 4—4 of Fig. 1.

I claim:

The ornamental design for a tire, as shown and described.
